TERMINAL ASSEMBLY

Harold Catron, Ralph L. Dashner, and Marion W. Morris, Logansport, Ind., assignors to E-B-M Manufacturing Company, Logansport, Ind., a corporation of Indiana

Application November 1, 1934, Serial No. 750,976

5 Claims. (Cl. 173—259)

This invention relates to terminal assemblies, and more particularly is directed to terminal assemblies for receiving relatively small-sized conductors for lighting circuits, ignition circuits, 5 switches, plug connectors and the like, in which rapidity and facility in the making of a positive mechanical and electrical connection is of prime consideration.

It has been customary, in terminals of the type 10 now in use, to employ binding posts having nuts threaded thereon for securing a conductor in positive mechanical and electrical connection with the terminal, or to provide terminals having lug portions receiving a threaded screw, the 15 end of the conductor being frictionally engaged between the lug and the lower surface of the screw head, or wrapped around the shank of the terminal post or screw and clamped in position by tightening of the terminal nut or screw. Such 20 terminals are open to numerous objections, since vibration may jar the terminal nut or screw loose, producing a faulty connection, or tension upon the conductor may overcome the frictional 25 resistance between the end of the conductor and the terminal, pulling the conductor away from the terminal.

In addition to these disadvantages, the time consumed in tightening the terminal connection is considerable, and ordinarily requires the use 30 of a tool, such as a screw driver or pliers. Further, the nut or screw may become loosened and drop off of the terminal assembly, thereby requiring the replacement of such part, or if the part becomes lost, the connection cannot be re- 35 established until such part is replaced.

The present invention, in its preferred form, 40 comprises a terminal assembly having resilient gripping means engageable with a camming surface for readily receiving the end of a conductor, which conductor is easily insertible into the terminal, and which cannot be withdrawn therefrom by tension or vibration upon the conductor.

The gripping means is urged into tighter gripping 45 engagement with the conductor when tension is placed upon the conductor in the present invention, but may be readily released when it is desired to disconnect the conductor from the terminal.

50 One object of the present invention is the provision of a terminal assembly of this type which is capable of being mounted upon a terminal bar or insulating block, as desired.

Another object of the present invention is the 55 combination of a terminal assembly capable of

being riveted in position upon any suitable supporting member, and wherein the securing means itself may act as a switch contact or terminal, if desired.

A further object of the present invention is to 5 provide a terminal assembly wherein a resilient gripping engagement is provided, without interposing any spring member into the path of the electrical circuit.

Another advantage secured by the present in- 10 vention is the provision of a terminal assembly wherein all the parts are formed from metal stampings or the like, and are capable of economical mass production and ready assembly.

Other objects and advantages of the present 15 invention will appear more fully from the following detailed description, which, taken in connection with the accompanying drawing, will disclose to those skilled in the art the particular construction and operation of a preferred form 20 of our invention.

In the drawing:

Figure 1 is a vertical sectional view through a preferred form of the invention;

Figure 2 is a view corresponding to Figure 1, 25 showing the manner in which the conductor is released from the terminal;

Figure 3 is an elevational view, partly in section, of a modified form of the invention; and

Figures 4 and 5 are optional forms of the em- 30 bodiment of the invention shown in Figure 3.

Referring now to Figures 1 and 2, in detail, we have provided a supporting member 10 which, in one form of the invention, may comprise a metallic terminal bar or strip, which is adapted to 35 have mounted thereon a metallic housing member 12, which preferably is formed of brass or the like, and which is substantially in the form of a hollow eyelet and may be formed by any suitable type of eyelet stamping machine.

The member 12 is provided with a frusto-conical hollow section 13, the small end of this section being provided with an inwardly extending annular flange 14 for a purpose to be hereinafter described. The member 12 is also provided with 45 an enlarged cylindrical section 15, which is joined to the frusto-conical section by means of an internal shoulder 16.

Disposed within the frusto-conical portion 13 of the member 12, and movable axially therein, 50 are two or more jaw members, indicated at 18, which, when moved toward the small end of the section 13, are forced toward each other to define a gripping portion therebetween. The external lateral surfaces of the jaws 18 are formed 55

to have sliding engagement along the internal surface of the section 13, whereby they are cammed toward each other as they are moved outwardly toward the small end of the section 13.

5 A suitable helically coiled spring 19 is inserted within the member 12, and is biased at one end against the jaw members 18. At its other end, the spring preferably is biased against a plate member 20, which plate member preferably is 10 press-fitted into the interior of the cylindrical portion 15 of the member 12, and has seating engagement against the shoulder 16. The member 20 thus fixes the spring 19 in position, and holds the jaw members 18 and spring within the 15 member 12. The use of this plate member is optional.

In order to support the terminal assembly upon the supporting member 10, we provide a rivet 22 having a head portion 23 of an external diameter 20 corresponding to the internal diameter of the cylindrical portion 15 of the member 12. The head portion of the rivet, indicated at 23, is moved into abutting engagement with the outer surface 25 of the plate member 20, and the peripheral edge of the cylindrical portion 15 of the member 12 is then spun over, as shown at 17, to engage over the under surface of the rivet head 23, whereby the rivet head is secured in fixed position within the member 12. The shoulder 16 forms an abutment against which pressure may be applied when the rivet 22 is inserted into position within the cylindrical portion 15 of the housing, and an external shoulder, indicated at 21, may be gripped by any suitable means to maintain the member 12 against movement while the ends 17 are spun over to grip the rivet.

40 The shank of the rivet extends through a suitable opening formed in the supporting member 10, and the opposite end of the rivet is turned over, as shown at 24, to clamp the terminal member 12 to the supporting base 10, as is well-known in the art.

A conductor 25, preferably of the insulated type 45 having insulation 26 thereabout, is adapted to be inserted through the cylindrical opening 27 formed in a releasing collar member 28, which releasing member has an outwardly extending peripheral edge 29 within the housing 12 adapted to have abutting engagement against the inwardly extending flange 14 of the member 12, whereby the member 28 is limited in its movement axially with respect to the member 12. The conductor 25 extends downwardly between substantially arcuate openings formed in the inner 50 meeting surfaces of the jaws 18, and when initially inserted into the terminal assembly, moves the jaws 18 axially of the member 12 into a position such that they may expand with reference to the side walls of the conical portion 13 of the member 12, whereby the jaws move apart a distance sufficient to allow the conductor 25 to be inserted downwardly through the central opening formed therebetween.

60 However, the spring member 19 immediately urges the jaw members axially outwardly of the member 12, thereby forcing them against the internal surface of the conical portion 13, and thus moving them into gripping engagement with the lateral surface of the conductor 25. The arcuate cutaway portions of the jaw members are provided with saw-tooth surfaces 30 adapted to have biting engagement into the surface of the conductor 25, whereby upon movement, or tendency 65 of movement of the conductor 25 outwardly of the terminal assembly, the jaws 18 are moved

toward the small end of the conical section 13, and consequently the saw-tooth surfaces 30 are moved into tighter gripping engagement with the conductor. This effectually prevents withdrawal of the conductor 25 by reason of tension placed 5 upon the conductor, or by reason of any vibration of the conductor or of the terminal assembly. The spring 19 assists in moving the jaws 18 toward the small end of the section 13, inasmuch 10 as the spring will move the jaws into engagement with the conductor after the conductor has been pushed into the position shown in Figure 1.

In Figure 2 we have disclosed the manner in which the conductor may be disengaged from the terminal. The collar 28, which is slidable with 15 respect to the terminal housing 12, has an outwardly extending flange portion 32 which may be readily gripped by the fingers, and this member may be moved inwardly of the housing 12, whereupon the flanged end 29 of the member 28 bears 20 against the upper surfaces of the jaws 18, moving the jaws inwardly against the pressure of the spring 19. This, in turn, causes the jaws to spread laterally away from each other, due to the increased internal area within the lower end 25 of the conical section 13. As a result, the jaws move out of gripping engagement with the conductor 25, and the conductor may thereupon be readily withdrawn from the terminal assembly.

It is obvious that any size of conductor capable 30 of entering into the opening 27 in the releasing collar 28 may be gripped by such a terminal assembly, since the relative position of the jaws 18 with respect to the surface 13 may be varied as desired, so that with a larger diameter of conductor the jaws will merely be positioned further inwardly of the member, and, as a result, will compress the spring to an extent whereby the jaws are forced into tighter engagement with the conductor. By reason of the toothed internal 40 surfaces forming the central substantially cylindrical opening receiving the conductor 25, a tight and effective gripping engagement upon the lateral surface of the wire is produced, and it has been found that the stress required to remove a 45 wire from such a terminal assembly exceeds the tension stress that may be exerted upon the wire, and the wire will either break or the teeth 30 will shear away a portion of the metal forming the conductor, before the conductor can be withdrawn, unless the releasing collar 28 is employed.

In Figure 3 we have disclosed a construction similar to Figures 1 and 2, except that the securing means in this particular embodiment of the invention is also employed for use as a switch 55 terminal or contact surface. In the embodiment of the invention shown in Figure 3, we provide an insulating supporting member 40, which member is adapted to receive a contact rivet 42, having an enlarged contact surface 43 which may be 60 polished or provided with any suitable contacting surface. The shank portion of the rivet 42 extends inwardly into the cylindrical portion 15 of the member 12, and is preferably formed with a cylindrical recess therein. The plate 20, corresponding to the plate 20 of the construction shown in Figure 1, having been press-fitted into the cylindrical portion 15, the spring 19 and remaining internal portions of the assembly within the housing 12 are held in fixed position. A suitable annular guiding collar 44, having a raised central portion 45 extending partially into the cylindrical recess 46 formed in the shank portion of the rivet, is provided with an annular arcuate- 70 ly curved channel surface 47, so that when the 75

5 rivet 42 is forced into engagement within the cylindrical portion 15 of the member 12, the edge of the cylindrical extending portion of the rivet is bent over as indicated at 48, within the annular channel-shaped portion of the member 44, and is thus forced into tight frictional engagement therewith, whereby the rivet 42 is fixedly secured to the member 12, and the member 12 and the rivet are positively positioned upon the insulating supporting member 40. The operating characteristics of the terminal assembly are the same as described in connection with Figures 1 and 2, and the shoulder 21 of the member may be employed as an abutment during the driving operation for securing the rivet in fixed position with respect to the housing 12.

In Figures 4 and 5, the same construction is disclosed, except that various shapes of contact surfaces, such as the concaved contact surface 50 of rivet 49 of Figure 4, formed as the head portion of the rivet, provides a smoother contacting surface for a rotatable switch terminal or similar contact engaging device. Preferably the rivet head is partially disposed in a recess 51 formed in member 40, with a spring 52 normally urging the head portion outwardly of the recess, whereby a resilient spring contact may be provided.

In Figure 5, we show a convexed contact surface 55 set into a recess portion 56 of the insulating member 40, the rivet head being entirely disposed below the planar surface of the insulating member 40. The rivet, in the embodiment shown in Figures 4 and 5, is secured to the housing 12 in the same manner as described in connection with Figure 3. The lower edge of the member 12 may be provided with a roughened surface or small lug portions for engaging the surface of member 40 to prevent rotation of the assembly.

40 It is thus apparent that we have provided a construction wherein a relatively small economical terminal assembly may be provided, which is capable of effecting and maintaining a positive mechanical and electrical connection 45 with a conductor, whereby vibration or tension upon the conductor will not cause release of the conductor from the terminal post, and wherein no auxiliary threaded means, such as a terminal nut or screw, with the accompanying time and expense involved in assembling and tightening the same, is necessary.

In addition, we have provided a terminal assembly wherein the conductor may be readily released without the necessity of unthreading a screw or loosening a terminal nut, and wherein connection to the terminal assembly may be made merely by inserting the conductor through the collar 28 and then passing it into the interior of the housing 12. No adjustments are necessary 60 after the terminal has once been mounted in position, and the terminal may be employed for various sizes of conductors.

In addition, we have provided a terminal assembly wherein the means for securing the assembly to a supporting member may also be employed as a contact surface for a switch terminal or the like.

Having described our invention in accordance with the patent statutes, what we claim as new and desire to secure by Letters Patent is:

1. A terminal assembly comprising a frusto-conical housing member open at both ends and having a plurality of jaw members therein, means defining a common central passageway between said jaw members for receiving a con-

ductor, a supporting member, means extending through said supporting member and having an enlarged head portion secured in the base of said housing member and closing the adjacent end of said member, said means serving to clamp 5 the peripheral edge of said housing member between said supporting member and said enlarged head portion, spring means biased between said enlarged head portion and said jaw member for urging said jaws toward the small 10 end of said housing member, and means for moving said jaw members inwardly against said spring means to release said conductor.

2. A terminal assembly comprising a housing having a frusto-conical end portion and an enlarged annular groove in the opposite end portion, jaw members mounted for axial movement in said end portion and defining a common central passageway therebetween, means secured in the groove in the opposite end of said housing and projecting therefrom, said means having an enlarged head portion rigidly secured in said housing, spring means in said housing biased between said head portion and said jaws for normally urging said jaw members outwardly of 25 said housing, a collar member having axial movement in the small end of said housing and adapted, upon inward movement, to move said jaw members against said spring means, and a supporting member, said projecting means being 30 clamped over one side of said supporting member to hold the peripheral edge of said housing defining said groove in fixed abutting engagement on the opposite side thereof.

3. A terminal assembly comprising a substantially tubular housing having an extending frusto-conical portion at one end thereof, an intermediate cylindrical portion, and an enlarged cylindrical portion at the opposite end thereof, an internal annular shoulder between said cylindrical portions, an annular plate member in said enlarged cylindrical portion abutting against said shoulder, means comprising a plurality of jaw members having a frusto-conical surface and having cooperating arcuate cut-away surfaces defining a central wire-receiving passageway, spring means biased between said plate member and said jaw members for wedging said members in said frusto-conical portion of said housing, means carried by and extending axially 40 outwardly of said housing for guiding a wire into said passageway and movable inwardly of said housing to force said jaw members out of gripping engagement with said wire, and means carried by the enlarged cylindrical portion of 45 said housing and securing said plate in fixed engagement with said shoulder for mounting said assembly upon a supporting member, the end of said housing adjacent said enlarged cylindrical portion being clamped between said mounting means and said supporting member.

4. A terminal assembly comprising a housing, said housing having an axially extending frusto-conical portion at one end thereof and having an enlarged cylindrical portion at the opposite end, cooperating jaw members within said frusto-conical portion forming a common central gripping opening and having their lateral surfaces engaging the interior surface of said frusto-conical portion, a spring within said housing biased at one end against the enlarged ends of said jaws, a rivet having its head portion disposed within said cylindrical portion of said housing, the peripheral edge of said cylindrical portion being bent over inwardly about said 70 75

- rivet head, the other end of said spring being biased against movement outwardly of said housing by said head portion, a collar having axial movement in the small end of said housing and 5 movable inwardly thereof to move said jaws toward the opposite end of said collar, and a supporting member, said rivet having its shank portion extending through said member and clamped over the opposite surface thereof to 10 support said assembly in fixed position on said member, said bent over edge of said housing being clamped between said head portion of said rivet and said supporting member.
5. A terminal assembly comprising a sleeve 15 member having an inwardly tapered frusto-conical portion at one end thereof and an en-

larged cylindrical portion provided with an in-turned peripheral flange at the opposite end thereof, wire gripping means within said member for receiving a wire inserted axially through said one end, a rivet member having an enlarged head portion locked in said cylindrical portion of said sleeve member and having a projecting shank, and a supporting member, said shank passing through and being secured over one side of said supporting member to clamp the flange 10 of said sleeve member between the opposite side of said supporting member and said head portion of said rivet.
